UNITED STATES PATENT OFFICE.

WILLIAM H. SMITH, OF TAMA CITY, IOWA.

SIGNAL-LANTERN.

SPECIFICATION forming part of Letters Patent No. 380,142, dated March 27, 1888.

Application filed May 4, 1887. Serial No. 237,032. (No model.)

To all whom it may concern:

Be it known that I, WILLIAM H. SMITH, a citizen of the United States of America, residing at Tama City, in the county of Tama and State of Iowa, have invented certain new and useful Improvements in Signal-Lanterns, of which the following is a specification, reference being had therein to the accompanying drawings.

This invention pertains to certain new and useful improvements in signal-lanterns; and it consists in the details of construction, combination, and arrangement of the parts, substantially as hereinafter fully set forth, and particularly pointed out in the claims.

In the accompanying drawings, Figure 1 is a side elevation of my invention, showing parts in dotted lines; and Fig. 2 is a cross-sectional view thereof.

In carrying out my invention my object has been to provide means for the ready signaling of trains both by night and day; and to this end I employ a metallic box or casing, A, in the front side of which is formed a door, a, through which the lamp is passed into said box or casing. In either side wall of this casing is secured an ordinary "bull's-eye," a', of heavy glass, the same being retained in position by an overlapping circular piece of tin or other metal reflector secured to the outside of the casing, as shown in Fig. 1. The box or casing is provided with a rearward tubular extension, b, near its upper end, the purpose of which will soon appear.

B is a signaling-glass of any color desired, but preferably red, set in a metallic frame, as shown, from the normally vertical lower end of one side of which projects an arm, b', the same being additionally braced or secured in position by means of a short brace-bar, as shown. The extreme outer end of this arm has a short right-angular slot, b'', formed therein for passing said arm on a cross-rod, b'', secured to the sides of the lantern, the same forming a pivotal bearing for said arm and frame, as will appear further on. The normal position of this signaling-glass is directly against or in close proximity to the inner side of the casing over the space occupied by the

of the glass bears against a rubber stop, C, secured in a tube projecting from the bottom of the lantern.

D is a cord or wire connected to the upper surface of the inclosing-frame of the signaling-glass B, whereby, upon pulling upon said cord or wire, the said glass will be elevated from its normal position over the bull's-eye, the same turning on the pivotal rod b'', whereon rests the slotted end of the arm b', as before stated, until one side of the frame strikes against a rubber stop, C', secured to the inner side of the lantern, after which the cord or wire is tightly secured to retain the glass in its raised or elevated position. This cord or wire is extended through the tubular extension b into the signaling office or depot where my lantern is located.

Thus far I have described only the means for signaling at night; but my invention, as above intimated, also embodies means for imparting any desired signal of danger during the day. This is accomplished by securing, by means of hinges d, one longitudinal edge of a signaling-board, E, to a projection or extension, e, of the box or casing A. To this signaling-board, which is of a color corresponding to the signaling-glass employed, is secured a cord or wire, D', the latter being connected to the cord or wire D, being first passed over a small pulley or wheel, d', secured on a cross-rod, d'', as shown.

From what has been said it will be seen that by operating the cord or wire D both the signaling-glass and board are operated simultaneously, and that the normal position of the signaling-glass is in rear of the bull's-eye, while the normal position of the signaling-board is in a vertical plane, thus admitting the same to full view. When the glass and board are in their respective normal positions, by pulling on the cord or wire D the glass will be raised from view, as above detailed, and the board will occupy a horizontal position in under the box or casing.

The signaling-glass can, together with its frame, be readily removed from the lantern by reason of the pivotal securing of the slotted arm b, when it is desired to clean or repair the same.

Having thus fully described my invention, what I claim, and desire to secure by Letters Patent, is—

1. The herein-described signal-lantern, consisting of the box or casing having a rearward tubular extension, the signal-glass frame having a detachable pivoted arm, the cord or wire connected to said frame, and the signaling-board hinged to one side of said box or casing, and the cord or wire connected to said board, substantially as shown and described.

2. The combination, with the lantern having the ordinary bull's-eye, of the signaling-glass having a frame provided with a detachable slotted extension-arm, the pivotal cross-

rod, and the operating cord or wire arranged to operate substantially as shown and described.

3. The combination, with the lantern and the pivotal cross-rod, of the signaling-glass, 20 the frame having a slotted arm, the rubber stops, and the operating cord or wire, all arranged substantially as shown and described.

In testimony whereof I affix my signature in presence of two witnesses.

WILLIAM H. SMITH.
